UNITED STATES PATENT OFFICE.

CHAIMSONOVITZ PROSPER ELIESON, DECEASED, BY CECILIA ANN ELIESON, EXECUTRIX, OF LONDON, ENGLAND.

ELECTRICAL ACCUMULATOR-PLATE.

1,357,548.

Specification of Letters Patent. Patented Nov. 2, 1920.

Application filed December 10, 1919. Serial No. 343,920.

To all whom it may concern:

Be it known that I, CECILIA ANN ELIESON, a subject of the King of Great Britain and Ireland, residing at London, England, am 5 executrix of the last will and testament of CHAIMSONOVITZ PROSPER ELIESON, late a subject of the King of Great Britain and Ireland, deceased, who has invented certain new and useful Improvements in Electrical 10 Accumulator-Plates, of which the following is a specification.

This invention relates to an improved electrical accumulator plate of the Planté or the like kind, which are built up by securing 15 a number of comparatively narrow strips of corrugated lead in a frame or support so that they lie one next to the other in planes at right angles to the vertical plane of the plate so constructed.

20 The object of the present invention is to increase the efficiency of the plate by providing, for relatively small overall dimensions, a comparatively great effective surface or area.

25 In the drawings:—

Figure 1. represents a length of thin lead sheet finely corrugated, with its edges provided with plain enlarged portions, and broken away at its ends.

30 Fig. 2. is an enlarged cross sectional view of the length of lead sheet showing one form of fine corrugation.

Fig. 3. is an enlarged cross sectional view 35 of the length of the lead sheet showing another form of fine corrugation.

Fig. 4. is a front elevation of a strip cut from the length shown in Fig. 1.

Fig. 5. is an end elevation corresponding to Fig. 4.

40 Fig. 6. is a front elevation of one form of electrical accumulator plate made up by arranging strips shown in Figs. 4 and 5 in a frame.

Fig. 7 is an end elevation corresponding 45 to Fig. 6.

Fig. 8. is a cross section on the line $x-x$ of Fig. 6 showing corrugations of the form depicted in Fig. 2.

50 Figs. 9 and 10 are front elevations of modified forms of plate, these constructions being particularly suitable for the larger types.

In carrying out the invention a length of thin sheet lead, of a thickness of from .001 55 inch upward, preferably .01 inch, is corru-

gated in any suitable manner known in the art for example by crimping rollers, to form a length (1) Fig. 1, having the corrugations (2) of fine pitch.

This length (1) of finely corrugated lead 60 sheet is provided at its edges with plain narrow portions (3) and (4) respectively, which are slightly thicker than the thickness represented by the amplitude of the corrugations.

The thin lead sheet may be finely corrugated, as shown in Fig. 2 so that the fine corrugations (2) are formed as flattened corrugations or pleatings, that is, the corrugations instead of being of the usual rounded 70 or open form are reduced in pitch to a minimum so as to leave only sufficient space between the folds or pleats to be filled up subsequently by the oxidation when undergoing the usual process of formation, or as shown 75 in Fig. 3, the corrugations may be of the usual form but of a fine pitch of the order of .05 inch.

The length (1) of finely corrugated lead sheet is cut into strips of $\frac{1}{8}$ inch to $\frac{1}{2}$ inch in 80 width, although this width may be greater or less as desired, and according to the width of the frame in which they are to be inserted as described hereafter.

A strip (5) cut from the length (1) is 85 shown in Figs. 4 and 5 from which it will be seen that the plain thickened portions (3) and (4) of the length (1), form thickened plain ends (6), (7) of the strip.

The strips (5) are arranged, preferably 90 vertically, surface to surface in closely spaced relation within a lead frame (8), Figs. 6—8 so that they lie in planes at right angles to the vertical plane of the plate so formed and with all of the corrugations 95 running longitudinally of the strips. The frame (8) may be provided with a lug (9) to enable it to be connected to another plate or to a terminal as known in the art.

The strips so arranged are secured at 100 their thickened ends to bars (10), (11) of the frame (8), by burning or in any other suitable manner well known in the art, the plain thickened ends (6) (7) in addition to facilitating burning of the strip in position, 105 serving as spacing members.

The flattened form of corrugation or plaiting is shown in this example, although the other form may be adopted if desired. When the form shown in Fig. 8 is adopted 110

the corrugations or plaitings may be such as to assume a thickness of about 2 millimeters from the tops of the plaits on one side to the tops of the plaits on the other side.

5 In the larger types of plate strengthening cross bars are employed as in Figs. 9 and 10.

Referring to Fig. 9 the frame (12) is divided into four panels (13), (14), (15), (16) by cross bars (17) and (18) the finely corrugated strips (5) being arranged, preferably vertically, surface to surface and in closely spaced relation within each of the panels (13), (14), (15), (16) so as to lie in planes at right angles to the plane of the plate so formed with all of the corrugations running lengthwise of the strips. The strips (5) are secured in the panels (13), (14) by burning their thickened ends (6), (7) to the bars (18), (19) respectively of the frame (12), and those in the panels (15), and (16) are secured by burning their thickened ends (7), (6) to the bars (18) and (20) respectively of the frame, the thickened ends (6), (7) in both cases acting as spacing members for the strips.

A lug (21) is provided on the frame (12) to enable it to be connected to another plate, or to a terminal as is well known in the art.

30 Referring to Fig. 10 a lead frame (22) is divided into two panels (23), (24) by a cross bar (25). The panels are filled in by the finely corrugated strips (5) which are arranged, preferably vertically, surface to surface in closely spaced relation within the panels so as to lie in planes at right angles to the plane of the plate so formed, with all of the corrugations running longitudinally of the strips.

40 The strips (5) are secured in the panels by burning their thickened plain ends (6), (7) to the bars (26), (27) respectively of the frame the thickened plain ends serving as spacing members in addition to facilitating securing of the strips (5) in position.

A lug (28) is provided on the frame (22) to enable it to be connected to another plate, or to a terminal as is well known in the art.

50 By arranging the strips vertically a free passage for the gases evolved is obtained.

I claim—

1. An accumulator plate, comprising a frame, and a series of independent strips of sheet lead in finely corrugated form arranged in such frame, with the strips in a plane at right angles to the plane of the frame, the spaces and ribs formed by the corrugations extending longitudinally of the strips.

60 2. An accumulator plate, comprising a

frame, and a series of independent strips of sheet lead in finely corrugated form arranged in such frame, with the strips in a plane at right angles to the plane of the frame, the strips being arranged with their 65 corrugated surfaces in parallelism, and the spaces and ribs formed by the corrugations extending longitudinally of the strips.

3. An accumulator plate, comprising a frame, and strips therein having finely corrugated surfaces and end portions of greater thickness than the maximum similar dimension of the corrugated surface, said strips being arranged in the frame with their end portions in contact and their corrugated 70 portions spaced from each other.

4. An accumulator plate, comprising a frame, and strips therein having finely corrugated surfaces and end portions of greater thickness than the maximum similar dimension of the corrugated surface, said strips being arranged in the frame with their end portions in contact and their corrugated 75 portions spaced from each other, the spaces and ribs formed by the corrugations of all 80 strips extending longitudinally thereof.

5. An accumulator plate, comprising a frame, and strips therein having finely corrugated surfaces and end portions of greater thickness than the maximum similar dimension of the corrugated surface, said strips being arranged in the frame with their end 85 portions in contact and their corrugated portions spaced from each other, the corrugated portion of each strip being in a 90 plane at right angles to the plane of the frame.

6. An accumulator plate comprising a frame and a series of independent strips of sheet material arranged in such frame, each 100 of said strips having a main length formed into fine corrugations extending longitudinally of and throughout said main length, each strip having end portions of increased thickness as compared with the main length 105 of such strip, the strips being arranged in the frame in parallel relation at right angles to the plane of the frame, with the end portions of adjacent strips in contact to space the main lengths of such strips.

110 In testimony whereof I have signed my name to this specification in the presence of two subscribing witnesses.
